UNITED STATES PATENT OFFICE.

EMERICH R. SCHWARZ AND ALPHONSE J. MARTENAY, OF CHICAGO, ILLINOIS.

TOOL-ROD.

1,350,425.

Specification of Letters Patent. Patented Aug. 24, 1920.

Application filed February 6, 1919, Serial No. 275,468. Renewed July 3, 1920. Serial No. 394,014.

To all whom it may concern:

Be it known that we, EMERICH R. SCHWARZ and ALPHONSE J. MARTENAY, citizens of the United States, residing at Chicago, in the county of Cook and State of Illinois, have invented certain new and useful Improvements in Tool-Rods, of which the following is a specification.

Our invention relates to tool rods and has for its primary object the provision of an improved actuating rod for tools which require pushing through tubular passageways frequently curved or bent or opening into small cramped quarters whereby the tool 10 may be driven around a curve or bend in the tube or may be bent through a convenient number of angles in order to gain access to the farther obstructed end of the tube without materially altering the thrust 15 transmitting function of the rod. A further object is the provision of an improved construction for tool rods whereby such a rod may be bent to a convenient number of degrees and be operated as a single rigid element in its bent condition. A further object is the provision of an improved tool 20 rod construction whereby the various parts thereof are so connected as to reduce to a minimum the cross sectional area at its joints and whereby simplicity, compactness and cheapness of manufacture are attained. Another object is the provision of an improved type of side plate for joining the 25 sections of the improved rod whereby the hand of the operator is protected from injury by reason of being pinched between the meeting surfaces of adjacent sections.

Other objects and advantages of the invention will appear from the following description taken in conjunction with the accompanying drawings which form a part of this specification and illustrate the preferred embodiment of the invention. The invention is particularly applicable for the 40 operation of flue cleaners for boilers, scraping tools for sewers and the like, and as a thrust rod for carrying cables through underground electric conduits.

In the drawings:

Figure 1 is a side elevation of the invention showing two full sections of the rod and portions of two other sections.

Fig. 2 is a side elevation of the parts shown in Fig. 1 illustrating the relation of 55 these parts in the bent condition of the rod.

Fig. 3 is a top plan view of the device of Fig. 1.

Fig. 4 is a fragmentary section of a modified form of the rod.

Reference numeral 10 indicates generally 60 the tool rod of the present invention comprising identical sections, 11, 12, 13 and 14. In the normal position of the rod the sections 11 to 14 comprise a series of straight bars aligned to form the straight rod 10, 65 these bars being rectangular in side elevation with the exception that corresponding corners of the ends of adjacent sections are beveled away as indicated at 15 and 16, the bevels being opposite each other on the same 70 side of rod 10 and extending not more than half way from the beveled side of rod 10 to the opposite side.

The sections are joined together by means of side plates 17 positioned in pairs, the 75 plates of each pair being disposed one on each side of the rod 10, in register with each other, and overlapping the abutted ends of adjacent sections. In the construction shown in Figs. 1, 2 and 3, the pair of plates 80 joining sections 11 and 12 for example are fixedly secured to section 12 by a rivet 18 traversing the lower left hand corner of section 12, entirely within the edges of the section and near the bevel 16; and also by a 85 rivet 19 one-half of which is embedded in the end of section 12 and the other half of which fits within a socket 21 cut for its accommodation in the adjacent end of section 11. The pair of plates 17 joining sections 90 11 and 12, or any other adjacent pair of sections in Figs. 1, 2 and 3, are fixed with respect to section 12, and section 11 is pivotally joined to the side plates 17 and section 12 by means of a pivot-pin 22, which 95 may be a rivet similar to the rivets 18 and 19 or passing loosely through section 11 at the same distance from either edge of rod 10 as rivet 18. Section 11 is pivotally movable with respect to section 12 and side plates 17, and in the same manner section 12 is pivotally movable with respect to section 13 and the side plates 17 are connected with sections 12 and 13; sections 13 and 14 and all other sections of rod 10 are similarly 100 connected. The bevels 15 and 16 extend inwardly from the ends of each section a distance sufficient to permit this pivotal movement but not so far as to allow one section to assume a right angle with an adjacent 105 110

- section; preferably these bevels are so shaped as to limit relative movement of adjacent sections so that these sections stand at an angle of approximately $22\frac{1}{2}$ degrees to each other. Thus, in a rod constructed according to the principles of our invention, the sections can be so pivoted with relation to each other that the first and fifth sections stand at right angles to each other, or the second and sixth; in other words the bevels are so shaped and rivets 18 and 22 so positioned, that any given section and the fifth one from it stand at substantially right angles to each other but are rigid against further bending by reason of contact between the bevels 15 and 16 of each of their abutted sections.
- In the modified form shown in Fig. 4 sections 31 and 32, having bevels 35 and 36 identical with bevels 15 and 16, are joined by pivot-pins 38 and 42 respectively, which engage side plates 17, each section being free for pivotal movement with respect to the other sections and to the side plates 17. The pivot-pins 38 and 42 occupy the same relative positions with respect to sections 31 and 32 as are occupied by rivet 18 and pivot 22 in respect to sections 12 and 11. Side plates 17 in Fig. 4 are also joined near the upper edges of sections 31 and 32, by means of a rivet 29, cylindrical in cross section and having its axis positioned in the vertical plane defined by the meeting end surfaces of sections 31 and 32 in the normal aligned positions of those sections. Inasmuch as sections 31 and 32 are both pivotally attached to the side plates 17, it may happen that in returning the sections to aligned position after they have been angularly offset with respect to each other, the sections will not be in true alignment. In order to bring them into alignment and also for the purpose of accommodating rivet 29 between the abutted ends of sections 31 and 32, we provide in the end of each section a recess 41 comprising angularly related beveled sides 43 and 44, each of which also stands at an angle with respect to the meeting end surfaces of the sections. In bringing the sections 31 and 32 into alignment the bevels 43 and 44 are operated as cams against rivet 29 to force that rivet to the bottom of the recess in one section, and subsequently to guide the other section into true alignment. In the form of invention illustrated in Fig. 4 the angular movement of the sections with respect to each other is limited by ultimate contact between bevels 35 and 36 and a slight amount of play is also permitted between the sections so that they may be offset with respect to each other and thus rendered more useful in very cramped quarters.

The side plates 17 in every instance extend beyond the edges of the rod 10, as illustrated in Figs. 1, 2 and 4, thereby forming a

guard to prevent pinching of the fingers of the operator either between abutted right angle ends of adjacent sections or between bevels 15 and 16 and bevels 35 and 36.

It will be understood that our tool rod 70 may be used as a flexible flue cleaner or for any other purpose where similar devices may or can be used to any advantage. For example, a flue cleaning device of any well known type may be attached to an end section of rod 10 and thrust through a flue, and should the flue be curved, the rod will bend in conformity with the curve as shown in Fig. 2, losing none of its thrust conveying advantages. Should the turn in the flue be 80 less than a right angle contact between those portions of side plates 17 which extend beyond the edges of the rod and the wall of the flue will limit curvature in the rod so that a thrust upon the rod is conveyed 85 around the turn to the flue cleaner on the farther end section. Attention is here drawn to the fact that those portions of side plates 17 which extend beyond the edges of the rod not only form guards for the protection of 90 the fingers of the hand of the operator but likewise form arcuate guide members which contact with the wall of the flue or conduit at a bent portion of the flue and guide the rod in its movement longitudinally of the 95 flue or conduit without offering obstruction to the movement of the rod. Our improved tool rod may also be employed in operating a device for cleaning tortuous sewers or for drawing wires through electric conduit, and in many other similar operations. A further advantage of our improved tool rod lies in the fact that it may be bent with respect to the axis of a straight flue so that at the bottom of a man-hole where space is lacking for 100 use of a straight rod or long sections of straight rod, the sections 11, 12, 13, 14, and so forth, of our rod may be bent to permit the whole rod to pass into the straight flue regardless of the fact that a fixed wall is 110 positioned close to and opposite the end of the flue. Obviously our rod may be constructed with its sections of any desired length; but in any one rod we prefer that the various sections be of equal length.

While we have illustrated and described the preferred embodiment of our invention, it is obvious that one skilled in the art may make modification thereof without departing from the spirit of the invention. We 120 wish therefore not to be restricted to the precise embodiment shown, except in so far as the same is limited in the appended claims.

We claim:

1. In a tool rod, the combination with aligned rod sections having ends abutting against each other through part of their meeting surfaces and beveled from each other through the remainder of their oppo- 130

site end surfaces, of side plates one on each side of said rod overlapping the sections, said sections being connected through the side plates at points remote from the edges 5 thereof to permit relative angular movement of the sections.

2. In a tool rod, the combination with alined rod sections having ends abutting against each other through part of their 10 meeting surfaces and beveled from each other through the remainder of their opposite end surfaces, of side plates one on each side of said rod overlapping the sections, said sections being connected through the 15 side plates to permit relative angular movement of the sections, said relative angular movement being limited by contact between the beveled end portions of adjacent sections.

20 3. In a tool rod, the combination with end abutted alined rod sections having corresponding portions of their opposite end surfaces beveled from each other, of side plates one on each side of the rod overlapping both 25 sections, said side plates being fixedly secured to one of the sections and pivotally connected to the other section.

4. In a tool rod, the combination of a pair of end abutted rectangular rod sections, a 30 portion of the opposite ends of said sections being beveled from each other at corresponding corners of said sections, of a pair of side plates one on each side of the rod, a pair of rivets extending through one section of the 35 rod and said side plates to bind the plates rigidly to said section and a pivot-pin traversing the other section and said side plates, one of said rivets and said pivot being positioned equidistant from a given edge of 40 said rod and adjacent the beveled end portions of the sections.

5. In a tool rod, the combination with spaced parallel side plates, of end abutted rod sections meeting within the perimeter

of the side plates, a pair of rivets each 45 traversing one of the sections and both side plates to pivotally connect the sections to the side plates; a rivet remote from the pivot-pins and having its axis positioned in the plane defined by the meeting ends of said 50 sections, said sections being each recessed for accommodation of the rivet, the recesses comprising each two angularly related flat surfaces upon any one of which the rivet is positioned to slide and to bring the sections 55 into alinement, said sections having corresponding opposite corners beveled from each other at a point remote from the rivet and adjacent to said pivots.

6. The combination with end abutted rod 60 sections having opposite portions of their end surfaces beveled from each other at corresponding edges of the sections, of a pair of side plates positioned one on each side of the sections and each overlapping both 65 sections and in register with each other, said side plates comprising circular disks of greater diameter than the width of the sections, of a binding rivet positioned near the beveled corner of one section and traversing 70 the side plates and section to bind the side plates fixedly to one section, a second rivet positioned near the opposite edge of the sections, having its axis positioned in the plane of the meeting ends of said sections and 75 binding the said plates to said one section, and a pivot-pin traversing the side plates and said second section and positioned near the beveled corner of said second section to pivotally connect the second section to the 80 side plates, said second section being recessed to receive one-half of said second pivot and having free play for pivotal movement between the side plates.

In testimony whereof we have affixed our 85 signatures.

EMERICH R. SCHWARZ.
ALPHONSE J. MARTENAY.
